UNITED STATES PATENT OFFICE.

JOHN B. WIARD, OF LYNN, MASSACHUSETTS, ASSIGNOR TO GENERAL ELECTRIC COMPANY, A CORPORATION OF NEW YORK.

STARTING-SWITCH FOR ELECTRIC MOTORS.

SPECIFICATION forming part of Letters Patent No. 780,547, dated January 24, 1905.

Application filed May 27, 1904. Serial No. 210,049.

To all whom it may concern:

Be it known that I, JOHN B. WIARD, a citizen of the United States, residing at Lynn, county of Essex, State of Massachusetts, have 5 invented certain new and useful Improvements in Starting-Switches for Electric Motors, of which the following is a specification.

My invention relates to electrical switches, and has particular reference to centrifugal 10 switches designed for use in alternating-current motors.

It is well known that in operating certain 15 types of alternating-current motors it is desirable to provide different circuit connections for starting and running. For this purpose some form of switching mechanism is usually employed by which the desired circuit changes may be made either manually or automatically.

The object of my invention is to provide a 20 centrifugally-operated switch adapted for this purpose and possessing a number of novel and highly-advantageous features.

One feature consists in the compact arrangement of the switch, whereby it may be assembled as a unit and mounted within a small 25 space at the end of the revolving member.

A second feature consists in so arranging a 30 switch that the movable contacts are entirely inclosed, thus enabling the switch to be used in places in which there would otherwise be danger of fire, due to arcing.

Another feature consists in so arranging the 35 resistance that absolutely no insulation is required in any part of the switch except between adjacent turns of the resistance.

Another feature consists in so arranging the 40 centrifugal member and its retaining-spring that the tension of the spring is not appreciably increased when the centrifugal member moves to close the switch-contacts, thereby enabling the centrifugal member to exert a firm pressure on the contacts.

Another feature consists in a novel form of 45 terminals adapted to give excellent electrical contact with simple construction.

My invention will best be understood by reference to the accompanying drawings, in which—

Figure 1 shows an end view of a centrifugal

switch arranged in accordance with my invention, the outer cap and one section of the resistance being removed. Fig. 2 shows a side elevation in cross-section of the same mounted on the end of the rotating member of a motor, the cross-section of the switch being taken on 55 the line 1 1 of Fig. 1; and Fig. 3 shows diagrammatically the circuit connections.

Referring first to Figs. 1 and 2, A represents the rotating member of an alternating-current motor carrying the coils *a* and mounted on 60 the shaft *S*, which is journaled in the bearing *B*. *a'* represents the end plate by which laminations of the rotor-body are clamped together. *C C'* represent two plates which are secured to end plate *a'* by means of the screws 65 *c*. Plate *C'* is cup-shaped to enable it to extend over the bearing *B*, and thus to economize space. Clamped firmly between plates *C* and *C'* is the cylindrical resistance *R*, which is made up of three sections, as designated by the 70 letters *r'*, *r²*, and *r³*, each of which is composed of an edgewise-wound strip of resistance material. These sections are separated by the two conducting-rings *I* and *J*, which are in electrical contact with the adjacent turns of the 75 resistance *R*. This construction enables excellent electrical contact to be obtained between the resistance-sections and the leads therefrom. The rings *I* and *J* are connected to the rotor-coils *a* by means of leads, one of which, *j'*, is 80 shown in Fig. 2. The rings *I* and *J* are each provided with portions *i* and *j*, which are bent into a direction parallel with the shaft. These portions form the stationary switch-contacts. The movable contact *H* is carried by a centrifugal member *D*, pivoted on plate *C* at *d*, as 85 shown in Fig. 1, and normally pressed against the adjustable stop *F* by means of the leaf-spring *G*, one end of which is clamped to the stationary support *g* and the other end of 90 which engages the pivoted member *D*. By means of the adjustable stop *F* the speed at which the pivoted member *D* operates may be adjusted as desired. It will be seen by the arrangement of the member *D* and spring 95 *G* that the tension of spring *G* is very little increased when the member *D* is moved to bring contact *H* into engagement with sta-

tionary contacts *i* and *j*. Therefore member D is enabled to bear with strong pressure on the contacts when moved outward by centrifugal force, insuring a good electrical connection.

The circuit arrangement is as shown in Fig. 3. *p* represents the primary winding of the motor, which I have shown as three-phase, connected to the three-phase line *L*. *a* represents the secondary winding which I have shown as three-phase *Y*-connected, two terminals of which are connected to the conducting-rings I and J through the leads *i'* and *j'*. The rings I and J are in electrical connection with the junction of resistances *r'*, *r²*, and *r³*, respectively, as has been heretofore explained. The outer ends of resistances *r'* and *r³* are both grounded on the end plates of the motor, as is indicated by the earth connection in Fig. 3. 20 The member D, which is in electrical connection with the movable contact H, is also grounded, as shown, as is also the third terminal of the secondary winding *a*. With the member D in the position shown it will be seen that the resistances *r'*, *r²*, and *r³* are connected in delta to the terminals of the secondary winding *a*. The motor secondary starts with the resistance properly connected in series with the secondary member. As 25 the motor speeds up and member D is moved outwardly by centrifugal force to bring contact H into engagement with contacts *i* and *j* it will be seen that the secondary member is directly short-circuited and the motor operates with a short-circuit secondary.

With the construction as heretofore described it will be seen that a compact arrangement is secured, that the movable contacts are completely inclosed by the resistance and the plates C C', so as to remove all danger of fire from arcing, and that owing to the arrangement of the resistance no insulation whatever is required between the resistance and its support or between the movable member and the frame. Excellent electrical contact is secured between the resistance terminals and the resistance leads and contacts by means of the flat conducting-plates, and by reason of the arrangement of the centrifugal 45 switch a proper contact is obtained when the switch is in its closed position.

Although in the diagram of connections I have shown a three-phase motor, it will be understood that my invention is not limited 55 to this specific number.

What I claim as new, and desire to secure by Letters Patent of the United States, is—

1. In a starting-switch for electric motors, a resistance having its extremities grounded 60 on the motor-frame and leads connected to one or more intermediate points on said resistance.

2. In a starting-switch for electric motors, a resistance having its extremities grounded 65 on the motor-frame and having leads con-

nected to two intermediate points so as to form a delta-connected resistance with one point of the delta grounded.

3. In a starting-switch for electric motors, a cylindrical resistance clamped between supporting-plates and in electrical contact therewith, and one or more leads connected to intermediate points on said resistance. 70

4. In a starting-switch for electric motors, a cylindrical resistance formed of edgewise-wound conducting-strips, supporting-plates clamped against the ends of said resistance and in electrical contact therewith, and one or more flat conducting-plates inserted at intermediate points in said resistance and adapted 75 to serve as terminals therefor. 80

5. In a starting-switch for electric motors, a centrifugally-operated switch member, and a resistance and supporting-plates therefor surrounding and inclosing said member. 85

6. In a starting-switch for electric motors, a centrifugally-operated switch member, a cylindrical resistance surrounding said member, and supporting-plates for said resistance serving with said resistance to inclose said 90 member.

7. In a starting-switch for electric motors, a centrifugally-operated switch member, a cylindrical resistance surrounding said member, and conducting-plates inserted at intermediate points in said resistance and having 95 bent portions adapted to be engaged by said member.

8. In a starting-switch for electric motors, a centrifugally-operated switch member, a cylindrical resistance surrounding said member and composed of sections of edgewise-wound resistance-strips, and flat conducting-plates inserted between adjacent sections and in electrical contact therewith and having 100 105 bent portions adapted to be engaged by said member.

9. In a starting-switch for electric motors, a starting resistance, and a centrifugally-operated switch member adapted to short-circuit 110 said resistance, said member and the extremities of said resistance being connected to a point on the rotor-winding of the motor through grounds on the motor-frame. 115

10. In a starting-switch for electric motors, a resistance connected at points intermediate of its extremities to points on the rotor-winding of the motor, and a centrifugally-operated switch member adapted to short-circuit said intermediate points on the resistance, said 120 member and the extremities of said resistance being connected to a point on said rotor-winding through grounds on the motor-frame.

11. In combination with an electric motor, a starting resistance therefor carried at one 125 end of the revolving member thereof and arranged to extend outwardly over the bearing at that end.

12. In combination with an electric motor, a starting resistance therefor, and supporting- 130

plates for said resistance secured to one end of the rotor, the outer plate being cup-shaped so as to extend outwardly over the bearing at that end of the rotor.

5 13. In combination with an electric motor, a cylindrical starting resistance carried at one end of the rotor and extending outwardly over the bearing.

14. In a starting-switch for electric motors, a pivoted centrifugally-operated switch member, and a leaf-spring engaging said member at a point near its pivot.

15. In a starting-switch for electric motors,

a pivoted centrifugally-operated switch member, and a restraining-spring therefor engaging said member at a point near its pivot so that a slight movement only of said spring is produced by the movement of said member to its closed position.

In witness whereof I have hereunto set my hand this 24th day of May, 1904.

JOHN B. WIARD.
